UNITED STATES PATENT OFFICE.

ALEXANDER WATSON, OF BEACHMONT, MASSACHUSETTS, ASSIGNOR TO BYRON C. LEAVITT, TRUSTEE, OF DUXBURY, MASSACHUSETTS.

GATE-VALVE.

1,016,461.

Specification of Letters Patent.

Patented Feb. 6, 1912.

Application filed September 27, 1911. Serial No. 651,484.

To all whom it may concern:

Be it known that I, ALEXANDER WATSON, a citizen of the United States, and resident of Beachmont, in the county of Suffolk and 5 State of Massachusetts, have invented new and useful Improvements in Gate-Valves, of which the following is a specification.

My invention relates to the construction of gate valves and has for its object the production of a simplified and reliable gate valve requiring a minimum of machine work and affording all the advantages incident to a clear straight passage for fluids when the valve is open.

15 In the drawings hereto annexed which illustrate my invention—Figure 1 is a vertical section of a valve showing some of the parts in elevation and others in dotted lines; Fig. 2 is a top plan view of the valve casing 20 with the hood thereof removed; Fig. 3 is a top plan view of the valve and its carrier; and Fig. 4 is a side view of the valve and its carrier and a portion of the operating means.

25 The valve casing comprises a main chamber C, an inlet branch I and outlet branch O, these two branches being preferably in the same axial line. The main chamber C extends at right angles to the inlet I and outlet O to a distance sufficient to provide a housing for the valve when the latter is fully open. A portion of the wall of the main chamber is made thicker than the remainder so that this portion indicated by C' 30 has an internal surface slightly smaller in radius than the general internal surface of the main chamber C. The surface of this portion C' constitutes the valve seat and extends for a substantial distance on either 35 side of the inlet opening. A guiding groove at each side of the interior of this main chamber C is provided by the ribs R, R', the tops of which are approximately flush with the cylindrical surface which would be 40 formed by a continuation of the contour of the valve seating surface at C'. The inlet and outlet openings I and O are internally threaded as usual. The upper end of the main chamber C is externally threaded and 45 the internal machining of the valve casing is accomplished by the introduction of a reamer which perfects the cylindrical surface of the said portion C' and at the same time reams a flat seat at that end of the 50 chamber C which may be called the bottom,

at C². It will be observed by reference to Fig. 2, that the introduction of such a reamer will leave the ribs R, R', untouched or at all events, will not remove enough material from them to affect their utility which 60 is presently to be described.

A cap or hood H screws onto the top of the chamber C and receives at its threaded upper end a threaded extension of the sleeve N which has also a similar threaded extension which takes the gland nut G.

65 A stem S provided with a collar S' and having its lower portion threaded at S² passes through the passage provided by the nut G, sleeve N, and cap H. The collar S' which is preferably integral with the stem S is confined between an internal shoulder h and the threaded projection of the sleeve N.

70 The gate valve shown in dotted lines in Fig. 1 is a hollow block generally cylindrical 75 in form provided with a lateral extension or protuberance V', which is turned or ground to a true cylindrical surface sized to fit accurately the cylindrical seat C'. The radial dimension of the valve V is greatest 80 on the side where the said portion V' is located, the opposite and remaining portion at V² being materially smaller in radius that is to say, contained well within a circle produced by the radius of the part V'. Thus 85 the gate valve as a whole fits loosely in the main chamber C of the valve casing. The lower end of the gate valve is squared off so as to rest and slide on the bottom seat C². The valve is provided with opposite slots V³ 90 which are inclined. A valve carrier consisting of the nut portion A and lateral extensions A', the nut portion being centrally threaded to receive the threaded portion S² of the valve stem is made of such dimensions 95 that it can be slipped sidewise through either of the slots V³ into the interior of the valve V.

100 The valve V may be economically manufactured by being die-cast since this mode of production will render it unnecessary to mill or slot the slots V³. The valve casting may then be chucked by means of an aperture v and the surface V' may then be turned or ground or both. Accurate facing 105 of the bottom of the valve V will not be necessary, die-casting being sufficiently accurate in its results.

110 In the specific construction herein shown the valve is assembled by first inserting the

carrier A into the interior of the valve V threading the portion S² of the stem S into the nut part of the carrier A, the cap H, sleeve N and gland nut G having previously been 5 assembled, then slipping the projecting arms A' into the guides formed by the ribs R, R', sliding the valve and its carrier into the chamber C and then screwing on the cap H.

When the valve stem S is turned so as to 10 raise the valve carrier the inclination of the slots V³ causes the cylindrical surface V' of the valve to be released from the valve seat C' and when the arms A' guided between the ribs R, R', reach the ends of the slots V³ 15 the entire valve will be lifted into the housing provided by the chamber C leaving a substantially clear passage for fluids from the inlet I to the outlet O. The reverse movement of the valve stem first lowers the 20 valve into place and then by the wedging action of the slots V³ slides the valve laterally on the bottom seat C until the cylindrical valve surface V' seats itself upon the cylindrical seat surface C'. It is considered 25 desirable to shape the valve casing so that a clearance chamber C³ will be provided beneath the valve V.

Generically speaking the lowering and 30 lateral wedging of a valve to its seat is an operation embodied in sundry old and well known structures but so far as I am informed these structures all involve a double valve of which the members seat in opposite directions and necessitate more parts and 35 more difficult machine work than has been found commercially practicable. By dispensing with one of the valve members I have obviated the necessity of making two such members with interlocking or telescoping 40 parts and by employing a cylindrical surface and seat on the single wedging member and the casing respectively I provide engaging surfaces of such ample extent (and yet in reasonably small compass) that only 45 moderate lateral pressure is required to secure the necessary tightness of the valve. By so modifying and adapting the structure of the valve member the single wedged member suffices, and the employment of a 50 single wedged member of cylindrical seating surface reduces the machine operations to a practical minimum, no more in fact than have to be performed in the manufacture of the common globe valve.

55 I claim—

1. In a valve, a casing provided with a cylindrical valve-seat, a cylindrical gate valve loosely fitting in the casing, the body of said cylindrical gate valve being hollow, and the 60 sides provided with opposite inclined slots, a valve carrier within the hollow valve having arms projecting through said slots into

guides on the interior of the valve casing, said guides, and externally manipulable means to raise and lower the carrier for the 65 purposes herein stated.

2. In a valve, a casing having a main chamber cylindrical in general contour, a valve seat, a portion of the interior surface of said chamber having a smaller radius 70 than the remaining portions, parallel ridges on either side of said chamber the tops of the ridges being substantially in the same cylindrical surface as the said valve seat portion, a smooth flat seat at the bottom of 75 the main chamber having a circumference substantially coincident with the valve-seat cylindrical surface, a cylindrical gate valve, having a face to fit the said valve and portion of the casing surface, the said valve 80 having its maximum radius at said face, the body of the valve being hollow and its sides provided with inclined slots, a valve carrier within the hollow valve having arms projecting through said slots into guides on the 85 interior of the valve casing, said guides, and externally manipulable means to raise and lower the carrier for the purposes herein stated.

3. In a valve, a casing having a cylindrical valve seat at one side, a hollow cylindrical gate valve loosely fitting in the casing and having a projecting sector on which is the seating surface, to fit said valve seat, the rear of the valve being smaller in radius to 90 afford clearance, and the sides thereof provided with opposite inclined slots, a valve carrier within the hollow valve having arms projecting through said slots into guides on the interior of the valve casing, said guides, and externally manipulable means to raise 95 and lower the carrier for the purposes herein stated.

4. In a valve, a casing having a cylindrical hollow seat at one side, a hollow cylindrical gate valve loosely fitting in the casing and having a projecting sector on which is the seating surface, to fit said valve seat, the rear of the valve being smaller in radius to 100 afford clearance, and the sides thereof provided with opposite inclined slots, a valve carrier consisting of a nut having two projecting arms, said nut within the valve, and the arms projecting through said slots into guides on the interior of the casing, said guides, and a threaded valve stem engaging 105 said nut, to raise and lower the carrier for the purposes herein stated.

Signed by me at Boston, Massachusetts, this 15th day of September 1911.

ALEXANDER WATSON.
